UNITED STATES PATENT OFFICE.

FERDINAND E. DAVIS, OF ENGLEWOOD, AND OSCAR ABERLE, OF CHICAGO,
ILL., ASSIGNORS TO SIGMUND OPPENHEIMER, OF NEW YORK, N. Y.

MACHINE FOR CLEANING INTESTINES.

SPECIFICATION forming part of Letters Patent No. 360,001, dated March 29, 1887.

Application filed October 5, 1886. Serial No. 215,393. (No model.)

To all whom it may concern:

Be it known that we, FERDINAND E. DAVIS, residing at Englewood, county of Cook, State of Illinois, and OSCAR ABERLE, residing at Chicago, in the county of Cook and State of Illinois, and citizens of the United States, have invented a new and useful Improvement in Machines for Cleaning Intestines, of which the following is a full description, reference being had to the accompanying drawings, in which—

Figure 1 is a plan of our machine. Fig. 2 is an end elevation of the same. Fig. 3 is a section at line *xx* of Fig. 1, looking to the left, 15 a portion of the parts being omitted. Fig. 4 is a section at line *yy* of Fig. 1, only a part of the machine being shown. Fig. 5 is an end view of the brushes and guide-rollers and the two small reels. Fig. 6 is an elevation showing a modification. Fig. 7 is an end elevation of the same. Fig. 8 shows another modification somewhat similar to that shown in Fig. 6. Fig. 9 is a detail.

This machine is primarily designed for 25 cleaning beef-intestines. We have prepared another application of even date herewith for a patent for a machine for a similar purpose, and those things herein claimed are in addition to those claimed in such other application.

Our present invention consists in the combination, with two brushes arranged to act upon opposite sides of the intestines, of two reels, one of which can be in motion while the 35 other is at rest, and a third reel arranged to be run in connection with either of the other reels, or to remain at rest, as required.

In the drawings, A is the main frame.

B is a portion of the main frame, from which 40 two arms, C C', extend outward. (See Figs. 2 and 5.)

a are ways on the frame B and arm C.

D is a bar which rests upon the ways *a*, the bar being provided with grooves on its under 45 side, and also with downward projections *b*, which rest upon the frame. The bar is held in place by means of bolts *d*, which pass through slots in that part of the frame marked B, and the arm C, and by eccentric levers *e*.

E is a shaft upon which is a brush, F, made in any suitable manner. The shaft is sup-

ported in bearings on posts which extend upward from the bar D. G is another bar corresponding with D, which rests upon ways on the frame B and arm C, and may be held in 55 place by bolts and eccentric levers, in the same manner as is bar D.

H, Figs. 1 and 5, is a shaft which carries a roller, I, which shaft is supported by posts which extend upward from the bar G. J, Fig. 60 5, is another brush upon a shaft, K, which is supported in bearings in the posts which support the shaft H. L is another roller on the shaft M, which is supported in bearings in the posts which support the shaft E.

N is a small reel on the shaft O. P is another small reel on the shaft Q. Both of the shafts O Q are supported in posts or standards R, which are secured to the main frame. S, Figs. 1 and 4, is a larger reel on a shaft, T, 70 70 which is supported in bearings on the main frame.

U is the main driving shaft, on which there are two pulleys, V W, one of which is fixed and the other loose. A' is another shaft supported in standards B', secured to the frame, 75 on which shaft there is a driving-pulley, D'.

E' is a sprocket-wheel on the main shaft U. F' is a small sprocket-wheel on the shaft A'.

G' (see Figs. 3 and 4) is a shaft supported 80 by bearings upon the main frame.

H' is a sprocket-wheel on the shaft G'. I' is a sprocket-wheel on the shaft O.

J' is a driving-chain on the sprocket-wheels E' F'.

K' is a clutch constructed in any well-known manner, whereby motion can be given to the shaft O and its reel N at pleasure. As shown, this clutch is operated by a lever, L', which need not be fully described.

M' is another sprocket-wheel on the shaft G'. N' is a sprocket-wheel on the shaft Q.

O' is a clutch on the shaft Q, by the use of which motion can be given to such shaft and its reel P at pleasure. This clutch, as shown, 95 is operated by a lever, P', in the usual manner, which lever need not be fully described.

Q' is a loose sprocket-wheel on the shaft T which carries the reel S. It is driven by a chain connecting it with a sprocket-wheel, W', 100 on the main shaft U.

R' is a friction-pulley spliced upon the shaft

T, which serves the purpose of a clutch, and is operated by a lever in the usual manner, which lever is not shown in the drawings. When this clutch-pulley is brought into engagement with the sprocket-wheel Q', motion will be given to the reel S.

T' is a worm on the shaft U, which engages with a worm-wheel, U', Fig. 4, on a short shaft, V', one end of which shaft carries a beveled wheel, f, which engages with a beveled wheel, g, on the shaft G'.

The main shaft U is driven by a belt upon the fixed pulley thereon, which belt is not shown in the drawings. Through the worm 15 T', worm-wheel U', and beveled wheels f, g motion is communicated to the shaft G', and through the sprocket-wheels H' I' the reel N is driven, and through the sprocket-wheels M' and N' the reel P is driven. The reel S is 20 driven from the main shaft through the sprocket-wheels W' and Q'. (See Fig. 1.) The shaft A' is driven from the main shaft by the sprocket-wheels E' F' and a driving-chain, J'. The brushes F J are both driven by belts h i 25 from the pulley D' on the shaft A'. The rollers I L are both driven from the shaft G' by means of belts j k, which run over pulleys l m on the shaft G'. The arrangement of the reels and their driving mechanism is such that the 30 large reel and either one of the small reels can be out of operation whenever desired. There are notches n in one edge of the reel-bars of each of the reels.

In use the ends of the intestines which are to 35 be cleaned are to be passed one after another by an operator in between the brushes F J and rollers I L, and the end of each intestine is to be carried, say, first to the upper reel, N, and to one of the holding devices on one of the bars. The 40 intestines passing between the brushes, which are to be rotated rapidly and in opposite directions, will be thoroughly cleaned. The reels P and S are first to be out of motion and the reel N in motion. When this reel N is full, it 45 is to be stopped by the use of the clutch. The intestines then for the time being are to be carried from the brushes to the reel P, which is in motion. While this is being done the intestines which have accumulated upon the 50 reel N can be transferred to the reel S, which may be used as a measuring-reel, and when this reel is full its motion can be stopped and the intestines can be removed therefrom by partially collapsing the reel. The bars o of 55 this reel are hinged to a head, p, and the arms or rods q are hinged at one end to the bars o and at the other end to a hub, r, which slides upon the reel-shaft T, so that by moving the hub a little the outer ends of the bars o will 60 be drawn somewhat toward the center, and the intestines can then easily be removed. The construction of this collapsible reel is more fully described in my former application. When the reel P is full, it can be stopped 65 and the intestines thereon can be transferred to the reel S, as before described. By the use of the several reels it is unnecessary to stop

the machine while removing the accumulated intestines.

One or both of the bars D G are to be adjusted so that the brushes and rollers can be adjusted nearer to or farther from each other, as desired. This adjustment may be secured by means of a screw and hand wheel, s, thereon, the bolts d and eccentric lever e being first 75 loosened. The means for this adjustment are fully described in our former application.

It is not necessary that the brushes and rollers be arranged as hereinbefore described. Neither is it necessary that rollers be used in 80 connection with the brushes, because a fixed resisting surface might be used in connection with each one of the brushes in place of the rollers.

We have shown in Figs. 6, 7, and 8 modifications which may be used, though we prefer the form first described. In Figs. 6 and 7 the brushes are arranged one a little above the table and the other in bearings in the table, and there is in connection with each brush a fixed 90 bearing-surface for the intestines, acting in connection with the brushes, and the intestines are to be drawn along in a horizontal direction instead of vertical. In Fig. 8 there is a similar arrangement, except that in place of the 95 fixed bearing-surfaces there are rollers to act in connection with the brushes, the intestines being fed horizontally.

In Figs. 6 and 7, a' represents a table. b' is one of the brushes located a little above the 100 table. This brush is upon a shaft, c', which is supported in three bearings, d' e' f', the latter, f', being supported by an overhanging arm, g'. h' is a rigid bearing-surface located below the brush b', and provided with lugs i, which 105 extend down into the table. j' are screws, by means of which the bar h' can be adjusted vertically. k' is another brush supported in bearings in the table, which may be adjusted vertically by means of screws in any known 110 manner. l' is a rigid bearing-surface overhanging the brush k'.

In Fig. 8 substantially the same thing is shown as in Figs. 6 and 7, except that instead of the rigid bearing-surfaces h' l' rollers m' n' 115 are shown. Devices for adjusting the roller m' and the brush k' are not shown in Fig. 8; but any known adjusting devices may be used.

In using the modification shown in Figs. 6, 7, and 8 the intestines are to be passed in between the brushes and the bearing-surfaces, substantially in the same manner as when the form first described is used, the intestines passing in a horizontal direction, or nearly so, to a reel or reels, which are not shown in Figs. 6, 125 7, and 8.

It is not essential that the small reels be made open, as shown, although this form is preferable. Cylinders or drums might be used.

Hooks or springs, as shown in our former 130 application, might be used as holding devices on the reels instead of notches.

Hoods may be provided over the brushes, which can be secured in any known manner.

What we claim as new, and desire to secure by Letters Patent, is—

1. In a machine for cleaning intestines, two reels, N P, one of which can be in motion 5 while the other is at rest, in combination with a third reel arranged to be run in connection with either one of the other reels, or to remain at rest, and means for supporting, connecting, and operating said reels, substantially as and 10 for the purposes specified.

2. In a machine for cleaning intestines, two

brushes arranged to act upon opposite sides of the intestines, in combination with three reels, N P S, and means for connecting and operating said reels, substantially as and for the 15 purpose specified.

FERDINAND E. DAVIS.
OSCAR ABERLE.
